UNITED STATES PATENT OFFICE.

LARKIN BRILES, OF LAKE CITY, CALIFORNIA.

ORCHARD-LADDER.

1,381,397.

Specification of Letters Patent. Patented June 14, 1921.

Application filed October 21, 1919, Serial No. 332,158. Renewed January 6, 1921. Serial No. 435,533.

To all whom it may concern:

Be it known that I, LARKIN BRILES, a citizen of the United States, residing at Lake City, in the county of Modoc and State of California, have invented certain new and useful Improvements in Orchard-Ladders, of which the following is a specification.

This invention relates to improvements in ladders especially adapted for use in picking fruit from trees.

An important object of this invention is to provide a ladder of the class described having means whereby the same may be quickly adjusted to various elevations for picking fruit from trees without the necessity of climbing the tree.

A further object of the invention is to provide an orchard ladder which may be positioned for use without being brought into engagement with the tree and marring the same.

A further object of the invention is to provide an orchard ladder having novel supporting means whereby the same may be employed on the sides of hills, etc.

A further object of the invention is to provide an orchard ladder which may be readily and conveniently collapsed and stored within a minimum of space when not in use.

A further object of the invention is to provide an orchard ladder which is efficient, of highly simplified construction and cheap to manufacture.

Other objects and advantages of the invention will be apparent during the course of the following description.

In the accompanying drawings forming a part of this application and in which like numerals are employed to designate like parts throughout the same.

Figure 1 is a perspective of an orchard ladder embodying my invention;

Fig. 2 is a plan view of the same collapsed;

Fig. 3 is a detail longitudinal section through the same;

Fig. 4 is a detail transverse section through the same.

In the drawings wherein for the purpose of illustration is shown a preferred embodiment of the invention the numeral 5 designates the base of the ladder which includes longitudinally extending horizontally arranged bars 6. As illustrated in Fig. 2 the bars 6 diverge outwardly slightly for ex-

tending over a maximum area and providing a stable base. The forward end portions of the bars 6 are vertically pivoted to a transversely extending connecting member 7 60 as indicated at 8. An intermediate connecting member 9 extending transversely of the base is provided in its end portions with elongated slots 10 receiving bolts 11 which also extend through the side bars 6 so that 65 the side bars may be adjusted transversely. Wing nuts 12 have threaded engagement with the bolts 11 and are adapted for securing the bars 6 in adjusted positions. When it is desired to collapse the device, the wing 70 nuts 12 are loosened to permit the free end portions of the bars 6 to be drawn inwardly whereby the base is caused to occupy a minimum of space when not in use.

A ladder generally designated by the numeral 13 includes a pair of standards 14 provided with metallic attaching feet 17 having their free end portions extended beyond the standards and bent as indicated at 18 for engaging spaced U-shaped staples or attaching devices 19 anchored to the forward connecting member 7. As illustrated in Fig. 1, the rear sides of the standards 14 are provided with inclined notches 20 adapted to receive the end portions of a cross bar 21 carried by a brace 22. The brace 22 includes standards 23 horizontally hinged to the intermediate connecting member 9 as indicated at 24.

For adjusting the ladder to various elevations, the cross arm 21 is engaged with the proper notches 20 in the rear side of the ladder.

Auxiliary supporting arms 25 each have one of their end portions vertically hinged 95 to the outer sides of the bars 6 as indicated at 26. The auxiliary supporting bars 25 are especially adapted for use when it is desired to use the orchard ladder on a hillside or on an incline for providing an additional bearing surface for the device. The free end portions of the arms 25 are provided with hooks 27 adapted to engage eyes 28 carried by the bars 6. The hooks 27 are engaged with the eyes 28 when it is desired to collapse the device.

At this point it will be noted that the ladder is capable of being used independently of the base and when so used the attaching feet 17 which extend beyond the 110 lower end of the ladder serve to anchor the ladder in a set position. In assembling the

orchard ladder, the bars of the base are arranged in the position illustrated in Fig. 1 and are secured in an extended position by the wing nuts 12. In the event that the 5 ladder is to be used on a hillside or an incline the auxiliary arms 25 are brought to a laterally extended position for affording additional bearing surface for the base.

The attaching feet 17 of the ladder are 10 now engaged with the staples 19 for pivotally connecting the lower end of the ladder to the base. It will be noted that the attaching devices 18 are inserted through the rear sides of the staples 19 and are thereby 15 prevented from accidental displacement during use. For arranging the upper end of the ladder at the desired elevation, the brace 22 is properly positioned with relation to the ladder.

20 When it is desired to fold the ladder, the brace 22 is swung to a horizontal position in parallel relation to the base and the ladder is detached and is positioned as illustrated in Fig. 2. The wing nuts 12 are now 25 loosened to permit the bars 6 to be drawn inwardly as illustrated in dotted lines in Fig. 2 for causing the base to occupy but a small amount of space.

It is to be understood that the form of 30 the invention herein shown and described is to be taken as a preferred embodiment of the same and that such minor changes may be made as will remain within the spirit of the invention and the scope of what is 35 claimed.

Having thus described the invention, what is claimed as new is:

1. An orchard ladder comprising a pair 40 of bars, a transversely extending member pivotally connecting the bars, an intermediate connecting member adjustably connected to the intermediate portions of the bars, a ladder connected to said first named connecting member, and a brace horizontally

hinged to said intermediate connecting member and engaging said ladder. 45

2. An orchard ladder including a pair of longitudinally extending bars, a transversely extending bar pivotally connected to the forward end portions of said longitudinally extending bars, an intermediate connecting bar extending transversely of said longitudinally extending bars and having elongated slots, bolts carried by said longitudinally extending bars and extending through said elongated slots, fastening devices mounted on said bolts, and a ladder mounted on said first named connecting bar. 50

3. An orchard ladder including a pair of base members, a connecting member pivoted to the forward end portions of said base members, an intermediate connecting member having elongated slots, adjusting devices carried by said base members and extending through said elongated slots, a ladder carried by said first named connecting member, and bracing arms hinged to the intermediate portion of said base members. 60

4. An orchard ladder including a base, a ladder mounted on the base, and bracing arms vertically hinged to the base and adapted to be swung outwardly of the same 65 for providing an additional bearing surface.

5. An orchard ladder including a base, a ladder horizontally and detachably hinged 70 to the base and provided on one side with spaced notches, and a brace carried by the base and engaging said notches. 75

6. A collapsible orchard ladder including a base, bracing arms vertically hinged to the 80 base and adapted to be swung outwardly from the same, coacting locking devices carried by said arms and said base and adapted for locking the free ends of the arms to the base, and a ladder detachably secured to the 85 base.

In testimony whereof I affix my signature.

LARKIN BRILES. [L.S.]
